(57) **CLAIM**

The ornamental design for a supporting arm for television receiver as shown and described.

DESCRIPTION

1.1 : Perspective view in a first position

1.2 : Rear perspective view

1.3 : Front elevation view

1.4 : Rear elevation view thereof

1.5 : Left elevation view thereof

1.6 : Right elevation view thereof

1.7 : Top plan view thereof

1.8 : Bottom plan view thereof

1.9 : Enlarged view taken from **1.1**

1.10 : Perspective view in a folded state

1.11 : Perspective view in an alternate position

1.12 : Perspective view in a state of use with additional display environment

1.13 : Perspective view in another alternate state of use position with additional display environment

1.14 : Front perspective view without environment in order to show aspects of the design not otherwise apparent

1.15 : Right perspective view thereof

The evenly spaced broken lines are directed to environment and form no part of the claimed design. The dot-dash line

(Continued)

and adjoining curvy line illustrate the bounds of the enlarged view and form no part of the claimed design.
